CLAIM

The ornamental design for a shirt tail trouser retaining belt, as shown and described.

DESCRIPTION

FIG. 1 is a perspective view of a shirt tail trouser retaining belt showing my new design, in a partially open condition; FIG. 2 is a front perspective view thereof with the broken lines shown for illustrative purposes only;

FIG. 3 is a top plan view thereof; and,

FIG. 4 is a front view thereof.

All surfaces not shown form no part of the claimed design. The indicia or broken lines shown on the figures are for illustrative purposes only and are hereby disclaimed as forming no part of Applicant's claimed invention.
